CLAIM

The ornamental design for a walking cane, as shown and described.

DESCRIPTION

FIG. 1 is a perspective view of the walking cane showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of a portion of the walking cane, taken along the dash-dot-dot-dash line in FIG. 2.

The broken lines shown in the drawings represent portions of the walking cane that form no part of the claimed design. The walking cane is shown with a symbolic break in its length. The appearance of any portion of the article between the break lines forms no part of the claimed design.
